UNITED STATES PATENT OFFICE.

CHARLES MORGAN OLMSTED, OF BUFFALO, NEW YORK.

SPINNING DEVICE.

1,138,142.

Specification of Letters Patent.

Patented May 4, 1915.

Original application filed October 2, 1909, Serial No. 520,678. Divided and this application filed May 18, 1912. Serial No. 698,120.

To all whom it may concern:

Be it known that I, CHARLES M. OLMSTED, of Buffalo, in the county of Erie and State of New York, have invented certain new and useful Improvements in Spinning Devices; and I do hereby declare the following to be a full, clear, and exact description of the invention, such as will enable others skilled in the art to which it appertains to make and use the same.

The primary object of this invention is to provide a simple and highly efficient spinning device for flying toys whereby less speed of the hand in unwinding the spinning cord is required, at the same time the stationary hand is relieved of the twist which is usually experienced in the act of unwinding.

In the accompanying drawings, Figure 1 is a view in perspective. Fig. 2 is a vertical longitudinal sectional view. Fig. 3 is a detail.

Referring to the drawings, 1 designates a flying toy which at its axial center has an opening to accommodate a rod or centering pin 2 which extends from a handle 3. On this rod or centering pin is mounted a spool 4 which is shown as having at its upper end two divergently arranged pins 5 which are designed to engage opposite edges of the blades of the toy at or near the axis thereof when positioned on the centering rod.

7 designates a cord the free end of which has a loop 8 which is designed to engage a hook 9 projecting from the lower end of the handle. This cord is wound around the spool, which latter is preferably reduced to accommodate the cord. The unwinding of the latter is facilitated by the employment of a hooked finger piece 10, which is shown as being made from a single piece of wire bent back upon itself and having hooks 12 for engaging the cord, the wire being looped to accommodate one or two fingers of the operator's hand. The cord may be of any suitable length, and if desired may be passed under the foot of the operator so that by pressing his leg downwardly foot-power

may be utilized for unwinding the cord from the spool. By securing the free end of the cord to the handle and pulling outwardly on the cord by means of the finger piece, or by foot-power, the speed of the hand is reduced to one-half for a given speed of unwinding the cord, and at the same time the stationary

hand, by which the handle is grasped, is relieved of the twist which it would get were the cord simply pulled on a straight line in a known way.

In using the foot to increase the spinning power, the foot may be placed upon the cord 7, between the hook 10, and the hook 9, and then depressed. If this is done, the foot slidably engages the cord. If it is preferred to have the foot fixedly engage the cord, the loop 8, is removed from hook 9, and cord 7, after being noosed over foot, is caught over hook 9, and the foot depressed. Hook 9, now becomes a means which slidably secures the cord to the lower end of the handle. Because of the pressure of the cord over hook 9, this hook performs the function of balancing the twist, which would, without it, disturb the aim of the supporting hand. While it is preferable to catch the cord over hook 9, when using the cord noosed to the foot, the virtue of hook 10, may be utilized without doing this.

It is obvious that besides using the foot to impart a portion of the power to the spin, it may be used to do all of the work. In this case the hook 10, is not pulled, but is held at a fixed distance from the handle. While the primary use of the hook 10, is to slidably engage the cord during a pull, its secondary use as a means for slidably engaging the cord and properly directing it away from the spool when foot power alone is used, is within the scope of the invention. Similarly the secondary use of hook 9 as a means for slidably securing the cord to the handle, is within the scope of the invention.

By means of my invention an operator is enabled to hold the toy in an easy manner to insure the direction of flight, and an accelerated speed may be imparted to the toy from the spool by the expenditure of comparatively little energy.

Although the primary object of the invention is to provide a simple and highly efficient spinning device for flying toys, the device may also be used to revolve spinning toys which do not fly.

I claim as my invention:

1. A spinning device for toys comprising a spinning part, a support for the latter, a cord designed to be wound on the spinning part and secured at its free end to the support, and a hook separate from said support for slidably engaging the cord at a point

between the spinning part and the end thereof which is fastened to the support.

2. A spinning device for toys comprising a spool, a support for the latter having a centering rod, a cord designed to be wound on the spool and secured at its free end to the support, and means for pulling the cord at a point between the spool and the end thereof which is fastened to the support, 10 said means movable relatively to said support.

3. In combination with a toy, means for rotating the same comprising a spinning part, a support for the latter, a cord designed to be wound on the spinning part and secured at its free end to the support, and means for engaging said cord and increasing the speed thereof at the spinning part over that of the engaging means.

20 4. A spinning device for devices comprising a handle, a centering rod extending from one end thereof, a spool mounted on said centering rod, a hook at the other end of said handle, a cord wound on said spool and having a loop at its free end for engaging said hook and a hook for slidably engaging the cord.

5. In combination with a toy having an axial opening, of a spinning device for said toy comprising a handle, a centering rod extending from one end of said handle and designed to extend through said axial opening, a spool, divergent pins carried by said

spool for engaging the toy at or near its axis, a cord wound on said spool and secured 35 at its free end to the handle, and a means for slidably engaging the cord between the spool and the fastened end of the cord.

6. A spinning device comprising a spinning part, a support therefor, a cord designed 40 to be wound on the spinning part, means on said support located axially with reference to the spinning part for slidably engaging the cord, and further means for slidably engaging the cord between the point where it 45 leaves the spinning part and the point where it passes through the first mentioned slidably engaging means.

7. A spinning device comprising a spinning part, a support therefor, a cord designed 50 to be wound on the spinning part, means for slidably engaging the cord between its extremity and the point where it is wound on the spinning part, and means for attaching the free end of said cord, after 55 winding, to said support at a point which lies approximately in an extension of the axis of the spinning part.

In testimony whereof, I have signed this specification in the presence of two subscribing witnesses.

CHARLES MORGAN OLMSTED.
